(57) **CLAIM**

The ornamental design for combined drip guard and cap for fogger, as shown and described.

DESCRIPTION

FIG. 1 is a bottom perspective view of the combined drip guard and cap for fogger of the instant invention.

FIG. 2 is a top perspective view thereof.

FIG. 3 is a front view thereof.

FIG. 4 is a rear view thereof.

FIG. 5 is a top view thereof.

FIG. 6 is a bottom view thereof.

FIG. 7 is a left side view thereof.

FIG. 8 is right side view thereof.

FIG. 9 is a top perspective view in use condition; and,

FIG. 10 is a bottom perspective view in use.

In the drawings, the broken lines show portions of a drip guard and fogger canister that form no part of the claim.
